(57) **CLAIM**

The ornamental design for a fingerprint reader, as shown.

DESCRIPTION

FIG. 1 is a perspective view of the fingerprint reader.

FIG. 2 is a top view of the fingerprint reader.

FIG. 3 is a front view of the fingerprint reader, the rear view being a mirror view thereof.

FIG. 4 is a side view of the fingerprint reader, the opposite side being a mirror view thereof; and,

FIG. 5 is a bottom view of the fingerprint reader.

The article is a fingerprint reader for use with a computer keyboard.
